UNITED STATES PATENT OFFICE.

JAMES S. WOOD AND O. WILLIS VAN OSDEL, OF ROCK ISLAND, ILLINOIS.

CHECK-ROW ATTACHMENT FOR CORN-PLANTERS.

SPECIFICATION forming part of Letters Patent No. 230,456, dated July 27, 1880.

Application filed May 3, 1880. (Model.)

To all whom it may concern:

Be it known that we, JAMES S. WOOD and O. WILLIS VAN OSDEL, citizens of the United States, residing at Rock Island, in the county 5 of Rock Island and State of Illinois, have invented certain new and useful Improvements in Check-Rower Attachments for Corn-Planters; and we do hereby declare the following to be a full, clear, and exact description of the 10 invention, such as will enable others skilled in the art to which it appertains to make and use the same, reference being had to the accompanying drawings, and to letters or figures of reference marked thereon, which form a 15 part of this specification.

Figure 1 a top plan of our improved attachment as applied to a corn-planter. Fig. 2 is a 20 transverse section of our improved attachment. Fig. 3 is a side elevation. Fig. 4 is a detached view.

Our invention relates to certain new and useful improvements in the class of check-rower attachments for corn-planters; and the invention consists in the novel combination and arrangement of parts, all as will be hereinafter 25 fully described, and specifically pointed out in the claims.

Referring to the accompanying drawings like letters of reference indicate like parts in 30 the several figures.

In the drawings, A represents a transverse beam mounted upon or forming one of the connecting cross-beams of the frame of a corn-planter, having secured at the ends thereof 35 the vertical uprights B B, in which is journaled the transverse shaft C, carrying upon its projecting ends the fixed driving band pulleys or wheels c c, over one of which passes the check-row cord, wire, band, strap, or chain C', composed of any suitable material, and either 40 plain or marked, for communicating motion to said pulley or wheel and shaft C, for a purpose hereinafter referred to.

D represents a sheave or pulley loosely 45 mounted upon a fixed shaft, d, secured in the lower ends of the metallic frame E. This frame is provided with a projecting screw-stud, e, which, in connection with the projecting end d' of the shaft d, forms a means by which said 50 frame, with its sheave or pulley, is secured to the upright B above the band pulley or wheel

C. Each of the uprights B is provided with a hooked-shaped slot, b, for the reception of the projecting end d' of the shaft d, and a vertically-elongated slot, b', for the reception of 55 the screw-stud e of the frame E, said frame being adjustably secured in said slotted upright by means of the screw-nuts and washers f f', all as clearly shown in Fig. 2.

The object of the sheave or pulley D is to 60 produce friction on the large band pulley or wheel c, and thus prevent the check-row cord, wire, band, strap, or chain C', passing over said pulley or wheel c, from slipping. Each of the uprights B is also provided with side 65 brackets, G G, having curved slots g g, in which are adjustably secured the sheaves or pulleys g' g' in front and rear of the large pulley or wheel c, for the purpose of taking up the slack and guiding and producing friction on the 70 check-row cord, wire, band, strap, or chain passing under said sheaves or pulleys g' g' and over the large pulley or wheel c.

H represents a pitman to be connected to the usual transverse seed-slide of a corn-planter 75 for imparting a reciprocating movement thereto. This pitman is connected with the crank h of the vertical shaft a by a universal joint, h', for the purpose of adapting the pitman to different positions on different forms of corn-planters and at the same time obviating friction in its application and operation.

The shaft a passes centrally up through the transverse beam A, with its upper end journaled in a metallic bearing-plate, a', secured to 85 said beam. Upon said shaft, above the beam A, is mounted a fixed bevel-gear wheel, I, with which the fixed segmental bevel-gear J, mounted on the revolving shaft C, intermittently engages for intermittently revolving the wheel 90 and shaft I a, and thus communicates a reciprocating movement to the seed-slide through the medium of the crank and pitman h H.

K represents a sliding bar mounted in the plate a', above the wheel I, and having a downwardly-projecting inclined lug, k, adapted to engage with the gear-wheel I for locking it in position until thrown out of engagement therewith through the medium of the segmental gear J. This segmental gear is provided with a beveled or wedge-shaped projection, j, at 95 its forward end, and which, as said gear is re-

volved with the shaft C, strikes against the projecting end k' of the sliding bar K, and forcing it backward until the lug k is thrown out of engagement with the gear-wheel I, and holding said bar in this position until the segmental gear is out of mesh with said wheel I, when a spring, k^2 , bearing upon said lug k , will again throw it into engagement with the wheel I, thus locking it in position and moving the sliding bar K forward for the segmental gear to engage with in its next revolution.

The object of locking the wheel I is to prevent any movement of the seed-slide or dropping mechanism from the jolting of the machine in passing over rough ground and ditches or any other causes when not in operation and between the regular intervals of dropping the seed, said locking mechanism rigidly securing the wheel and holding the seed-slide, together with its mechanism, from moving in either direction.

L represents a clamp, in which one end of the check-row cord, wire, band, strap, or chain is secured in order to secure or adjust it at different lengths, according to the distance across the field. The clamp L is provided with a hook, ring, or pulley, l, playing on a horizontal bar, l', staked at each end of the field, whereby said check-row cord, wire, band, strap, or chain is adapted to adjust or change its position to suit the position of the planter after it has been driven across the field and back.

The pulleys or wheels c c are marked, as shown at c², to show where the machine drops the seed, so that the marks c³ on the check-row cord, wire, band, strap, or chain may be adjusted relative thereto, whereby the operator can tell at any point on the field where the hills are dropped.

The operation of our improved attachment is as follows: The check-row cord, wire, band, strap, or chain being passed over one of the wheels or pulleys c and under the sheaves or pulleys D g' g' and stretched across the field, the machine is started, when the check-row cord, wire, band, strap, or chain will revolve the wheel or pulley c and shaft C, which, through the segmental gear J, will communicate motion to the wheel I and shaft a, and thus operate the seed-slide or dropping mechanism through the medium of the crank and pitman H h. When the machine has crossed the field the check-row cord, wire, band, strap, or chain is transferred to the wheel or pulley c on the opposite side of the machine in going back across the field.

We are aware that wire, rope, or chain have been heretofore used in check-row attachments for corn-planters; but they are objectionable, for the reason that the wire kinks and breaks, the rope stretches and shrinks, while the chain is too heavy.

Having thus fully described our invention, what we claim as new, and desire to secure by Letters Patent, is—

1. In a check-rower attachment for corn-planters, the combination, with the pulley or wheel c and the check-row cord or band passing over the same, of the adjustable sheave or pulley D, arranged directly above the pulley or wheel c, substantially as and for the purpose herein shown and described. 70

2. In a check-rower attachment for corn-planters, the combination, with the pulley or wheel c and the check-row cord or band passing over the same, of the adjustable sheaves or pulleys D g' g', substantially as and for the purpose herein shown and described. 75

3. In a check-rower attachment for corn-planters, the combination of the upright B, provided with the slots b b', the metallic frame E, provided with the sheave or pulley D, shaft d d', screw-stud e, and nuts and washers f f', substantially as and for the purpose herein 80 shown and described.

4. The combination, with the large pulley or wheel c, of the side brackets, G G, provided with the curved slots g g and the sheaves or pulleys g' g', adjustably secured in said slots, 90 substantially as and for the purpose herein shown and described.

5. In a check-rower attachment for corn-planters, the combination, with the shaft C, wheel or pulley c, and check-row cord or band 95 passing over said wheel or pulley, of the slotted upright B b b', slotted side brackets, G G g g, and the adjustable sheaves or pulleys D g' g', substantially as and for the purpose herein shown and described. 100

6. In a check-rower attachment for corn-planters, the combination, with the gear-wheel I, of locking mechanism for securing said wheel in position, and a revolving segmental gear, J, having a beveled or wedge-shaped projection, j, for operating said locking mechanism and gear-wheel, substantially as and for the purpose herein shown and described. 105

7. In a check-rower attachment for corn-planters, the combination of the shaft C, provided with the pulley or wheel c, and segmental gear J, having the forward beveled or wedge-shaped projection j, sliding bar K, having projecting end k' and inclined lug k , spring k^2 , shaft a, having bevel-gear wheel I, and the 110 crank and pitman h H, for operating the dropping apparatus of a corn-planter, substantially as and for the purpose herein shown and described. 115

8. In a check-row attachment for corn-planters, the combination, with the crank and pitman h H, for operating the dropping apparatus, of a universal joint, h', for connecting said crank and pitman, substantially as and for the purpose herein shown and described. 120

9. In a check-rower attachment for corn-planters, the combination, with the check-row cord or band, of the clamp L, provided with a hook, l, or its equivalent, adapted to play on the horizontal bar l', substantially as and for the purpose herein shown and described. 125

10. In a check-row attachment for corn-

planters, the combination, with the seed-slide-operating mechanism, of a metallic strap or band stretched across the field, and through the medium of which the said operating mechanism is actuated, substantially as specified.

11. In a corn-planter, the combination, with the seed-slide-operating mechanism, of automatic locking devices for rigidly securing the said seed-slide mechanism from movement in any direction when not in operation, said lock-

ing devices being actuated directly through the seed-slide-operating mechanism, substantially as and for the purpose specified.

In testimony whereof we affix our signatures in presence of two witnesses.
